UNITED STATES PATENT OFFICE

2,646,225

SKULL CRUSHER

Lawrence Te Desco, Frank, Pa.

Application October 29, 1951, Serial No. 253,744

3 Claims. (Cl. 241—273)

1

This invention relates to new and useful improvements in impact crushing devices such as utilize a weight that is swung by or dropped from a boom, sometimes referred to in the trade as skull crushers, and it is among the objects thereof to provide for the use of a multiple of weights which are successively dropped upon an object to be crushed to thereby increase the capacity by lowering the overall time of work accomplished by such apparatus.

The invention will become more apparent from a consideration of the accompanying drawings, constituting a part hereof, in which like reference characters designate like parts, and in which:

Fig. 1 is a side elevational view of a skull crusher embodying the principles of this invention;

Fig. 2 a top plan view of a combination boom and conveyor mechanism;

Fig. 3 a side elevational view, partially in section, of the boom of Fig. 2 taken along the lines 3—3 of Fig. 2; and

Fig. 4 a transverse section of the boom taken along the line 4—4 of Fig. 3.

With reference to Fig. 1 of the drawings, the structure therein illustrated comprises a conventional tractor-type truck 1 for rendering the unit mobile, having a cab 2 mounted for swivel movement on a turret 3 of the tractor 1. On one end of the cab 2 is mounted a boom 4 which is pivoted at 5 and supported by a cable 6 connected to the boom 7, which cable passes over a pulley 8 to a winding drum in the cab 2, which is not shown and constitutes no part of this invention.

Mounted in the boom 4 is an endless conveyor 9 which carries the shafts 10 of drums 11 to which is secured a cable 12, a loose end of which is attached to a weight 13 that is designed to strike an object 14 to crush the same. The conveyor 9 is driven by a motor or engine 15 in the cab by a conventional drive connection and, as shown by the dot and dash circular lines, the weights pass through an opening at the bottom of the boom and travel upwardly to the opening at the top of the boom beyond the end of the conveyor 9 and drop by gravity on the object 14.

As will more clearly appear from Figs. 2, 3 and 4 of the drawing, the drums 11 for winding the weight cables 12 are provided with flanges 16 having gear teeth that engage racks 17 of the boom so that when the shafts 10 carrying drums 11 are moved forward on the boom

by the chain 9, the drums will revolve by virtue of their gear tooth engagement with the rack 17, and by revolving wind up the cable 12, pulling the weight 13 so that the latter moves at a faster rate than the conveyor 9. The racks 17 terminate short of the sprocket wheel 18 at the top of the boom, and the weights 13 would tend to revolve the drums 11 in the direction to release the weights before they were delivered to the opening above the sprocket wheels 18. This is prevented by the use of pawls 19 that engage the teeth of the drum flanges 16, the pawls being biased by springs to maintain constant engagement with the teeth of the drum flanges 16. When the weight 13 is delivered to the opening at the top of the boom, it will travel in the path illustrated by the dot and dash lines until it falls by gravity, causing the cable 12 to unwind in the direction where the pulley 20 is free of the pawl 19. The weight 13 drops on the object to be crushed and is then dragged forward toward the rear of the boom in the manner shown in Fig. 1. As the drum 11 on the conveyor chain 9 passes to the point of tooth engagement with the rack 17, the cable 12 will immediately wind on the drum 11 until the weight 13 is drawn to the top of the boom.

The structure is given stability by the use of ties 20, Fig. 2, and is of course not subjected to any great stress or loads other than the winding, lifting and transportation of the weights from the bottom opening to the top opening of the boom.

By means of the above described mechanism, a number of crushing weights, there being three shown for illustration only, may be utilized to greatly decrease the time ordinarily involved in the crushing of objects by means of dropping weights. It is evident from the foregoing description of the invention that skull crushing devices made in accordance therewith may be of simple construction and of simple operation.

Although one embodiment of the invention has been herein illustrated and described, it will be evident to those skilled in the art that various modifications may be made in the details of construction without departing from the principles herein set forth.

I claim:

1. In a skull crusher, a boom comprising a plurality of side members, an endless conveyor chain mounted between said members, drums mounted for rotation on said conveyor chain, gear racks disposed below the upper strand of said conveyor chain in the path of movement of said chains

and gear teeth on said drums interacting with the teeth of said rack whereby the drums revolve while being conveyed by the chains from one end to the other end of the boom, spring biased pawls for engaging the teeth of the drums to prevent rotation thereof in one direction, cables connected to said drums having crusher weights at one end thereof, and means for driving the conveyor chain whereby the crusher weights are lifted from the ground by rotation of the drums and conveyed along the boom to the top thereof to fall by gravity on the article to be crushed.

2. In a skull crusher, a boom having a plurality of endless conveyor chains mounted for rotation intermediate the ends thereof, drive means for said chains, a plurality of cable drums mounted between the chains to be conveyed thereby, gear racks disposed below the upper strand and in the path of movement of the chains, gear teeth on the drums for engaging the gear racks to be rotated while traveling with the conveyor chain from one end of the boom to the other, spring biased pawls for engaging the teeth of the drums to prevent rotation thereof in one direction, cables connected to said drums having crusher weights at one end thereof, and means for locking said cable drums against rotation in one direction after they have passed out of engagement with the teeth of the racks comprising a spring ratchet pawl for engaging the teeth of the drums.

30

3. In a skull crusher for manipulating a plurality of crusher weights, a boom mounted for swivel movement on a support, a plurality of endless conveyor chains mounted in said boom, a gear rack disposed below the upper strand of said conveyor chain, cable drums journaled between the links of said chains having a tooth flange interacting with the teeth of the gear rack to revolve the drums while passing from one end of the boom to the other, spring biased pawls for engaging the teeth of the drums to prevent rotation thereof in one direction, cables secured to the drums having crusher weights connected at the opposite end thereof and drive means for said chain, the boom having open spaces for the crusher weights at the respective ends thereof whereby the weights are lifted and drawn from below the boom to the upper strand of the conveyor chain while being wound on the conveyor drums as they travel to the opening at the upper end of the boom to be released for crushing action, said conveyor chains having cross members for supporting the crusher weights while being conveyed thereon.
